UNITED STATES PATENT OFFICE.

JOHN W. STOKES, OF OKLAHOMA, OKLAHOMA, ASSIGNOR TO R. C. STOKES, OF DALLAS, TEXAS.

GARBAGE-BURNING FURNACE.

1,182,511.

Specification of Letters Patent. Patented May 9, 1916.

Application filed December 2, 1915. Serial No. 64,609.

To all whom it may concern:

Be it known that I, JOHN W. STOKES, citizen of the United States, residing at Oklahoma, in the county of Oklahoma and 5 State of Oklahoma, have invented certain new and useful Improvements in Garbage-Burning Furnaces, of which the following is a specification.

This invention pertains to new and useful improvements in garbage burning furnaces.

The object of the invention is to provide a furnace of particular design involving, certain fundamental elements in the nature 15 of a fuel grate and coöperating baffle wall, together with an extension of the grate beyond said wall; an auxiliary incinerating grate and retaining wall; and the disposition of a smoke stack outside of the furnace 20 communicating with the furnace in such a manner as to cause a circulating draft whereby the incinerating operation will be more efficiently and expeditiously carried out.

25 A further object of the invention is to provide a furnace of the character described that will be substantial and efficient, and one in which the several parts will coöperate in a harmonious manner.

30 With the above and other objects in view the invention has relation to certain novel features of construction and operation, an example of which is described in the following specification and illustrated in the 35 accompanying drawings, wherein:

Figure 1 is a front elevation of the furnace, Fig. 2 is a horizontal cross sectional view taken on the line $w-w$ of Fig. 1, Fig. 3 is a transverse sectional view taken on the line $a-a$ of Fig. 2, and Fig. 4 is a longitudinal sectional view taken on the line $y-y$ of Fig. 2.

In the drawings the numeral 1 designates a base or bottom from which a front wall 2 and a back wall 3 extend upwardly and are connected by side walls 4 and 5 respectively, also projecting upward from the base. The side walls are connected by an arch 6 of refractory material which extends 45 from the front wall to the rear wall and forms the roof of the combustion chamber inclosed by the base 1 and walls 2, 3, 4 and 5. Over the arch a platform 7 constructed in accordance with the practice in this art, 50 is provided. An opening 8 is provided in

the top of the furnace and closed by a cover 9. By removing the cover garbage and other waste matter may be dumped into the furnace. The rear wall 3 is curved downward and forward from a line substantially coincident with the base of the arch and merges into a dished portion 10 in the upper surface of the base. This curved portion is under the opening 8 so that the garbage will have a tendency to work forward as it is 65 fed into the furnace.

At the front end of the base an ash grate 11 is disposed over a pit 12. Doors 13 give access to the grate and pit. Incinerated waste matter on top of the pile in the furnace chamber may be raked onto the grate at intervals so that the ashes will fall into the pit below, while the unconsumed matter will rest upon the grate. This latter matter may be consumed readily by opening the 75 lower door 13.

Adjacent the side wall 4 a fuel grate 14 is arranged and extends rearward from a fire opening 15 in the front wall. An extension grate 16 in the form of a continuation of the grate 14 is also provided. The grates are over a pit 17 which is closed at its front end by a door 18; while the fire opening is also closed by a door 18. On the side of the grate 14 opposite from the wall 4 a baffle wall 19 extends rearward from the front wall 2 and from the base 1 to the arch 6. Between the walls 4 and 19 a fuel fire box is formed over the grate 14, the greater portion of the grate 16 projecting beyond 85 the rear end of the baffle wall. Along the opposite side of the furnace contiguous to the wall 5 auxiliary grates 20 are arranged and separated from the dished portion 10 by a low retaining wall 21. Access is had 90 to these latter grates through an opening 22 in the front wall and a pit 23 is provided under said grates. Doors 24 close the opening 22 and the front end of the pit. The wall 21 prevents liquids running over onto 95 the grates from the portion 10.

Outside of the furnace a smoke stack or flue 25 is constructed either against or adjacent the wall 5. The furnace has communication with the stack through a horizontal duct 26 disposed at the spring of the arch 6, whereby it is elevated above all the grates and creates an efficient draft. Access to the stack may be had through a clean-out door 27 disposed below the duct. 105 110 115

In operating the furnace a fire is first built upon the grate 14, fuel being introduced through the opening 15. A considerable draft will be produced by the stack 5 which causes the heat units to circulate in the furnace chamber in the general direction of the duct 26, the rear end of the baffle wall 19 being rounded to promote circulation. The furnace is heated to the proper 10 temperature, when the cover 9 is removed and garbage and other waste matter introduced through the opening 8. Owing to the forward curvature of the rear wall 3 the matter falling thereon has a tendency to 15 work forward into the dished portion 10. The smoke and gases are drawn across the furnace and upward toward the draft opening or duct 26. Sufficient heat is had in the furnace to consume all gases and smoke and 20 to rapidly incinerate the garbage and waste matter. All oils and liquids will be held in the portion 10 until evaporated; while the incinerated matter is raked onto the grate 11 at intervals. 25 A certain portion of the garbage may be used for fuel and for this purpose the extension grate 16 is provided so that a portion of each deposit of garbage may be raked thereonto if desired. The grates 20 may be 30 used for burning the garbage which may be raked on the same and by opening the lower door 24 sufficient oxygen is admitted to promote the combustion of the matter on the grates 20. 35 It is obvious that most any condition encountered in the incineration of garbage and other waste matter may be handled to the best advantage in this furnace and further that it may be operated at a minimum expense owing to its economic fuel arrangements.

What I claim, is:

1. In a garbage burning furnace; a combustion chamber having a base and front, side and back walls rising from the base together with an arch connecting the walls and

provided with an opening whereby garbage may be introduced into the chamber; a fire box within the chamber in proximity to one wall thereof; a baffle wall extending upward from the base of the chamber adjacent the fire box and also extending rearward from the front wall, but terminating short of the back wall of the chamber; a grate in the fire box having an extension projecting beyond the rear end of the baffle wall; and a stack disposed adjacent the wall opposite that adjacent the fire box, said stack having communication with the chamber. 55

2. In a garbage burning furnace; a combustion chamber having an arched top provided with an opening for admitting garbage; a base at the bottom of the chamber; a fuel grate at one side of the chamber; a vertical baffle wall extending rearward from the front wall of the chamber and co-operating with the grate and its adjacent wall to provide a fuel fire box; an extension fuel grate projecting beyond the baffle wall; an ash grate at the central front portion of the base; auxiliary garbage grates at the side of the chamber opposite to the fuel grates; a retaining wall contiguous to the auxiliary grates; and an exterior stack having communication with the chamber through a duct 70 over the auxiliary grates. 75

3. In a garbage burning furnace; a combustion chamber having an arched roof provided with an opening for admitting garbage; a base at the bottom of the chamber having a dished portion into which the rear wall of the chamber is merged; a fuel grate at one side of the chamber, said chamber having a draft duct at its opposite side; a vertical baffle wall adjacent the fuel grate; 85 an auxiliary garbage grate on the duct side of the chamber; a retaining wall separating the auxiliary grate from the dished portion of the base; and a stack communication with which is had through the duct. 90

In testimony whereof I affix my signature.
JOHN W. STOKES.
